UNITED STATES PATENT OFFICE.

GEORGE E. CHANDLER, OF TAUNTON, MASSACHUSETTS.

ACETYLENE-GAS GENERATOR.

No. 823,103.

Specification of Letters Patent.

Patented June 12, 1906.

Application filed August 15, 1902. Serial No. 119,732.

To all whom it may concern:

Be it known that I, GEORGE E. CHANDLER, a citizen of the United States, residing at Taunton, in the county of Bristol and State 5 of Massachusetts, have invented a certain new and useful Improvement in Acetylene-Gas Generators, of which the following is a specification, reference being had therein to the accompanying drawings.

10 This invention relates to improvements in acetylene-gas generators.

One object of the invention is to so construct a generator wherein acetylene gas can be generated that feeding of the calcium carbid 15 is positively prevented when the generator is open to the atmosphere.

Another object of the invention is to so construct a feed-controller for controlling the feeding of calcium carbid that the same is 20 rendered inoperative by the opening of the generator.

Another object of the invention is to improve the construction of the carbid-feeding mechanism.

25 Another object of the invention is to improve the construction of the machine with relation to the prevention of the escape of gas into the atmosphere from the various joints or connections.

30 Other objects of the invention will appear from the description and claims.

The invention consists in a gas-generator provided with a feeding device, a controller for such feeding device, and means for holding 35 the controller in an inoperative position while the generator is open.

The invention also consists in the construction of the controller and in the combination therewith of means for rendering the controller inoperative.

The invention also consists in the construction of the feeding device.

The invention still further consists in the general novel features of construction of the 45 machine and in the peculiar combination of parts, as shall hereinafter be more fully described, and pointed out in the claims.

Figure 1 of the drawings represents a front elevation of the improved acetylene-gas machine, portions thereof being broken away to 50 more clearly illustrate the construction of some of the parts. Fig. 2 represents a plan view of the same. Fig. 3 represents a detail side view of the counterweighted lever and connecting parts. Fig. 4 represents an en-

larged sectional view of the feeding device and its coöperating mechanism. Fig. 5 represents an enlarged cross-sectional view of the casing for the feed-lever and its shaft; and Fig. 6 represents a vertical sectional view 60 of the upper portion of the hopper, showing the construction of its neck and the closure thereof, taken on a line at right angles to that shown in Figs. 1 and 4.

Similar characters of reference designate 65 corresponding parts throughout.

In carrying this invention into practice my main object has been to prevent the escape of gas into the atmosphere whether such escape is occasioned by leaks in joints of the 70 machine in which movable parts are mounted or from failure to close an opening through which gas may escape, my other objects, of equal importance therewith, being to improve the general construction of the ma- 75 chine.

In the drawings, 5 represents the gas-generating chamber, having the feeding-drum 6 furnished at its top portion with the carbid-supply-opening fitting 7, closed by the cap 8, 80 screwed thereon. This chamber 5 is preferably mounted on a base 9 and is provided with a clean-out 10 of any usual construction.

The construction of the supply-fitting 7 is more particularly shown in Fig. 6, which 85 shows the channel 7' formed in the wall of this fitting and connecting with the upper end thereof, the cap 8 being furnished with an annular compartment 8', in which gas in passing toward the joint between the cap 8 90 and the fitting 7 may be led to the upper end of the channel 7'.

Within the drum 6 is mounted the hopper 11, from which extends the contracted portion or tube 12 and the frame 13, on the bars 95 14 of which is sustained the cone 15, positioned beneath the portion or tube 12, and on this tube 12 works the tubular feed gate or valve 16, having pins, as 17, or their equivalents, the lower end of this tubular gate 16 100 resting on the cone 15.

From the drum 6 depends the cylinder 18, having an open end around which is fixed the plate 18', having the depending rims 19 19 furnished with serrated edges.

At the side of the chamber 5 is mounted the water-supply inlet 20, connecting with said chamber by a suitably-trapped supply-pipe 21 and provided with the gas-escape pipe 22.

On the drum 6 is secured the casing 23, which connects with the interior of the drum, and in this casing is pivoted the arm 24, having a forked end engaging under the pins 17 5 and provided with the exterior lever 25, having the weight 26 and the roller-bearing 27. The casing 23 is formed and packed to prevent the escape of gas in the manner shown and is provided with the gas-escape 10 pipe 28, connecting with a similar pipe 29, leading from the channel 7' of the fitting 7, whereby the gas escaping from these parts is conveyed to the main escape-pipe 30, by which it is directed into the atmosphere outside the building in which the generator is 15 stationed. Reference to said figure will show that the casing 23 has a compartment 23', with which the pipe 28 connects, the shaft 24' of the lever 24 being journaled in the 20 casing and compartment and carrying the disks 24² and 24³, the latter being movable, and the spring 24⁴, which tends to force these 25 disks apart and against the walls of the casing and its compartments to more fully close the shaft-bearings therein, as these disks can be more accurately fitted than can the shaft, the lever 25 being fitted and secured onto the outer end of the shaft 24'.

The gas-storage mechanism comprises a 30 casing 31, having the compartment 32, connected by the pipe 33 with the drum 6, and having the pipe 34, leading upward, the partition 35 in this casing supporting the pipe 36, open at its ends and connected with the 35 outer gas-main 37. Exteriorly this casing is supplied with the inlets 38 and 39, the water-level below the partition 35 being indicated by the line *a a*, while the water-level above said partition is indicated by the line *b b*.

40 The gas-escape 30 connects with the compartment of the casing 31 below the partition 35 to provide for the escape of gas reaching this compartment.

Within the casing 31 is movable the inner 45 inverted bell 40, having the top 41, and the inner gas-bell 42, having openings, as 43 43, and covering the open ends of the gas-inlet pipe 34. In the top 41 is secured the tube 44, which works over the guide-rod 45, fixed in 50 the partition 35.

From the upper end of the pipe 33 and partially sustained by the bracket 46 of the casing 31 extends the standard 47, carrying the pivotally-mounted counterweighted lever 48, one arm of which is connected with the lever 25 by the wire 49, which works through a perforation in said arm and has its lower end enlarged to limit its movement independently of said lever 25.

60 From any suitable and ordinary support, of which 50 is a part, depends the bracket 51, in which the lever 52 is pivoted, one end of this lever being connected by the connection 53 with the weighted end of the lever 48, 65 while the other end of said lever 52 is flexibly

connected by the connection 54 with the cap 8 for closing the carbid-supply opening 7.

The hopper 11 is usually recharged with calcium carbid before the previous charge therein is wholly exhausted. To effect this 70 recharging, it is necessary to remove the cap 8 from the fitting 7. If now the feeding of the carbid from the hopper into the water contained in the chamber 5 be continued, gas would be generated and a large portion 75 thereof would escape through the opening of the fitting 7. In order that the continued generation of gas should be prevented, I connect the cap 8 with the feeding-control device, preferably as shown in the drawings, 80 whereby the weighted end of the arm 48 lifts the arm 25 of the feed-control mechanism to thus depress the yoke 24 from any possible lifting action on the feed-gate 16 and to sustain these parts in such inactive position until the cap 8 is replaced and the escape of gas is prevented.

After the supply of calcium carbid has been placed in the hopper 11 and the cap 8 has been screwed into place on the fitting 7 90 the gas-bell 41 is generally at or about its lowest point of movement, and the downward movement of the arm 25, until the bearing 27 rests on said tank, causes the proportionate lifting of the feed-gate 16, thus 95 permitting a predetermined amount of carbid to fall from the cone 15 in annular distribution into the water contained in the chamber 5, the action of the water on said carbid generating gaseous globules, the specific gravity of which being less than that of the water causing them to rise toward the surface of the water. In their upward movement these globules are successively disrupted as they drag over the serrations of the lips 19 100 and the undissolved matter therein liberated for further action by the water. The gas thus generated accumulates between the lower portion of the chamber 6 and the upper portion of the hopper 11 and then enters 110 the pipe 33, passing into the compartment 32 of the storage-tank and thence through the pipe 34 into the chamber 42 of the gas-bell 41 until the accumulation of gas in such chamber causes the lifting of the bell to the 115 point where the feed-controller permits the feed-gate 16 to close.

From the upper part of the bell 41 the gas passes down the pipe 36 and into the service-main 37, from whence it is distributed to the 120 various points of use.

By the connections from the several joints where any escape is possible the escaping gas is conveyed by the pipes 28, 29, and 30 and by the pipe 22 to the exterior atmosphere. 125

When the gas-bell is lifted by undue pressure of gas to bring the openings 43 above the water-level *b b*, the gas escapes from the inner bell into the outer bell and passes down through the pipe 55 (more clearly shown in 130

Fig. 5 of the drawings) to the compartment below the partition 35 and is thence conveyed to the outer atmosphere by the escape-pipe 30.

5 Having thus described my invention, I claim as new and desire to secure by Letters Patent—

1. An acetylene-gas generator comprising a chamber having a feed-hopper provided with a charging-opening, a feeding device contained within the chamber beneath said feed-hopper, an actuator for said feeding device, a counterbalance for such actuator for drawing the same out of the operative position, a closure for the feed-hopper charging-opening, and means for connecting said closure and the counterbalance.

2. An acetylene-gas machine comprising a chamber having a feed-hopper provided with a charging-opening, a feeding device located within the chamber beneath said feed-hopper and furnished with a vertical gate, a lever for actuating the gate, a counterbalance for such lever, and a closure for the feed-hopper connecting with such counterbalance.

3. An acetylene-gas machine comprising a chamber having a feed-hopper provided with a charging-opening, a feeding device contained therein and having a vertically-movable gate located beneath the feed-hopper and a lever working through a suitable fitting on said chamber, the exterior portion of the lever being adapted to engage with and to be actuated by a gasometer, a counterbalance for the exterior portion of the lever, and means for connecting said counterbalance with the closure for the feed-hopper.

4. An acetylene-gas generator comprising a carbid-chamber having a feed-opening and a discharge-opening, a closure for the feed-opening, a conical distributer located beneath the discharge-opening, a circular guard embracing the distributer, means for moving the guard, and connections between such means and the closure for the feed-opening, whereby the movement of the guard is controlled by said closure.

5. An acetylene-gas generator comprising a carbid-chamber having a feed-opening and a discharge-tube, a water-tank into which the discharge-tube extends, a closure for the feed-opening, a distributer located beneath the discharge-tube, a cylindrical gate working on the discharge-tube, actuating means for the gate working through the wall of the water-tank, and exterior connections be-

tween said actuating means and the closure for the feed-opening.

6. An acetylene-gas machine comprising a chamber having a feed-opening, a screw-cap 60 for closing the opening, a feeding device within the chamber, an actuator for the feeding device, and a counterbalance positively connected with the actuator and with the screw-cap whereby the actuator is withdrawn from 65 operative position by the removal of the cap and is returned to position by the replacing of the cap, without the actuation of additional mechanism.

7. An acetylene-gas machine comprising a 70 chamber having a feed-opening, the hopper 11 within said chamber and having the pipe 12, the tubular gate 16 movable on said pipe, the lever 24 mounted on the shaft 24', and having a fork for engaging the pins 17 of the 75 gate, the lever 25 fixed on the outer end of the shaft 24', the counterweighted arm 48 pivotally mounted and connected with the lever 25, the lever 52 pivotally mounted and connected with the arm 48, and the cap 8 80 connected with the lever 52, as and for the purpose described.

8. The combination with the feed-chamber having the fitting 7 furnished with the channel 7' and the escape-pipe 29, of the cap 85 8 adapted to close said fitting and having the compartment 8', as and for the purpose described.

9. The combination with the chamber 6 and the fitting 23 secured thereto and having 90 the compartment 23', of the waste-pipe 28 connected with said compartment, as and for the purpose described.

10. An acetylene-gas generator composed 95 of a chamber having a feed-hopper provided with a charging-opening, a feeding device located within the chamber beneath said feed-hopper, an actuator for said feeding device, a closure for said feed-hopper, a counterbalance connected to said closure and said actuator to render the feeding device operative, but allowing the feeding device to assume an inoperative position when the closure is removed by the action of the counterbalance on the actuator.

105 In testimony whereof I affix my signature in presence of two witnesses.

GEORGE E. CHANDLER.
